C. R. GREEN,
SEPARATOR TANK FOR VACUUM CLEANING SYSTEMS.
APPLICATION FILED FEB. 8, 1908.

984,810.

Patented Feb. 21, 1911.

UNITED STATES PATENT OFFICE.

CARL R. GREEN, OF DAYTON, OHIO, ASSIGNOR TO THE NATIONAL VACUUM CLEANING COMPANY, OF DAYTON, OHIO, A CORPORATION OF OHIO.

SEPARATOR-TANK FOR VACUUM CLEANING SYSTEMS.

984,810.

Specification of Letters Patent. Patented Feb. 21, 1911.

Application filed February 8, 1908. Serial No. 414,969.

To all whom it may concern:

Be it known that I, CARL R. GREEN, a citizen of the United States, residing at Dayton, in the county of Montgomery and State of Ohio, have invented certain new and useful Improvements in Separator-Tanks for Vacuum Cleaning Systems, of which the following is a specification.

My invention relates to improvements in vacuum cleaning apparatus and particularly to receiver or separator tanks therefor.

The object of the invention is to greatly simplify the construction as well as the means and mode of operation of such devices whereby they will not only be cheapened in construction, but will be more efficient in operation and unlikely to get out of repair.

With the above primary and other incidental objects in view as will appear from the specification, the invention consists of the means, mechanism, construction, and mode of operation or their equivalents hereinafter described, and set forth in the claims.

In the drawings Figure 1 is a vertical sectional view of the assembled tank. Fig. 2 is a transverse sectional view on line α — α of Fig. 1. Fig. 3 is a bottom plan view of the tank or separator, and Fig. 4 is a somewhat diagrammatic view showing the relation of the separator tank to the other parts of the cleaning apparatus.

Like parts are indicated by similar characters of reference throughout the several views.

The purpose of the device is to form a receiver for the dirt and dust taken up in the cleaning operation, and to separate the dust from the current of air in its passage through the tank.

The tank proper comprises two members an upper portion 1 and a lower portion 2 provided respectively with peripheral flanges 3 and 4 by which said portions are connected. The lower portion 2 is preferably formed slightly conical as shown, and is provided with a closure 5. An inlet nozzle 6 is located in the lower portion 2 which nozzle is connected with the cleaning device or hand piece 7, see Fig. 4. An off take 8 leads from the upper portion 1 of the tank.

Secured within the tank and intermediate the inlet 6 and outlet 8 is an inverted sack 9 of fabric or other porous material, through which the air must pass in its course from

the intake 6 to the outlet 8. The sack 9 serves to filter the air, the dust particles being deposited on the interior of the sack, the air passing through the porous walls and out through the outlet 8 to the pump 10. The sack 9 is made with a laterally projecting brim 11 of fabric, somewhat in the form of a peripheral flange about the mouth thereof. The diameter of the sack 9 is somewhat less than that of the tank. The sack is secured in position by the engagement of the lateral brim 11 thereof between the flanges 3 and 4.

To maintain the sack 9 central in the tank and to prevent the walls thereof from coming in contact with those of the tank when the sack is in an inflated condition, and thus reducing the filtering surface of the sack, a metal collar 12 is provided the interior diameter of which is less than that of the tank 70 and substantially equal to that of the sack. The inner edge of the collar is provided with a bead 13 upon which the sack bears, thus obviating danger of chafing or undue wear upon the sack material. The collar 12 rests 75 on the brim 11 of the sack 9 and between the flanges 3 and 4. Packing 14 is also inserted between the flanges, and the sack, the collar 12 and the packing 14 all clamped in position by bolts or rivets 15 connecting the 80 flanges 3 and 4.

Supported on arms 16 in the portion 2 of the tank, and in direct line with the discharge of the intake 6 is a deflector 17 conical in form and adapted to arrest and distribute the inrushing current of air, permitting the particles of dirt carried thereby to settle in the bottom of the portion 2.

It has been found in practice that without the use of the deflector 17 the inrushing current of dirt laden air will continually agitate the dirt deposited in the bottom of the tank and keep the dirt in violent motion within the tank, and an undue amount of the larger particles will be deposited on the interior of the sack 9, thus clogging the filter. The deflector 17 being in direct line of the incoming air current will receive the impact thereof and arrest the current of air, and the dirt carried thereby will settle 100 into the bottom of the tank where it will be protected by the deflector 17.

In order that the deposit of dirt may be readily removed from the tank, the closure 5 is removable and comprises a plate, secured 110

in position by dogs 18 pivoted to ears 19 on said closure plate 5 and engaging a flange 20 about the mouth of the tank. The dogs 18 each have an arm 21 engaging over 5 the flange 20 and an arm 22 having therein an adjusting screw 23 bearing on the closure plate 5, whereby the operation of the screws 23 will oscillate the dogs 18 on their pivots and cause the arms 21 to bear on the flange 10 20, drawing the plate 5 into close contact with the mouth of the tank. The dogs 18 each have two inward projecting arms 21, 22. The arm 21 projects over the upper side of the cover plate to a limited extent, and 15 when in place over the flange. The lower arm 22 projects under the cover plate. In other words, each dog 18 has on its inner side a recess within which the cover plate and flange project, or the dogs might be said 20 to be substantially 7 shaped, one arm of the 7 being short and engaging on the upper side of the flange 20, the long arm extending below the cover plate. The screws 23 are screwthreaded in the arm 22 and bear 25 upon the cover plate. By operating the screws 23 the long arm of the dog is forced away from the cover plate, but the dog turning on the pivotal connection with the ears 19 and causing the short arm 21 to bear 30 strongly on the flange 20 will draw the cover plate more closely to the receptacle by a prying movement in which the dog 18 is a lever, the short arm 21 on the flange being the fulcrum, the screw 23 in the long arm 35 the power and the cover plate engaged through the ears 19 the work.

Attached to the interior of the sack 9 is a rod 24 which is suspended from the top 40 thereof when the sack is inflated by the air passing there through, but when the sack is collapsed the rod 24 will drop down within reach when the closure 5 is removed and may be used to shake the sack 9 to loosen the particles of dust adhering thereto.

45 The tank is located between the pump 10 and the hand piece 7, being connected to the pump 10 by the off take 8. A conduit 25 connects the hand piece 7 with the intake 6. The pump being operated draws a current of air from the hand piece 7 through the tank to said pump. The current of dirt laden air enters the tank through the inlet 6 and is discharged downward, striking the deflector 17 by which it is arrested, the dirt 50 particles being allowed to settle into the bottom of the tank, while the air with some of the more fine dust particles pass upward within the sack 9, the air passing through the porous walls of said sack, and the dust 55 particles being deposited on the interior thereof. The air passes from the tank through the outlet 8 to the pump. To remove the dirt deposit the closure 5 is removed by loosening the screws 23 when the 60 dogs 18 may readily be disengaged from the

flange 20, permitting the dirt to drop from the tank. The rod 25, which will project through the mouth of the tank when the tank is open may be shaken to free the filter sack 9 of any dust particles clinging thereto, and upon the replacement of the closure 5 the device is in condition for further operation.

70 From the above description it will be apparent that there is thus produced a device 75 of the character described, possessing the particular features of advantage before enumerated as desirable, but which obviously is susceptible of modification in its form, proportion, detail construction, and arrangement of parts without departing from the principle involved or sacrificing any of its advantages.

80 Having thus described my invention, I 85 claim:

1. In a separator tank for vacuum cleaning systems, a receptacle divided medially into separable sections an inverted filter sack 90 located wholly within the upper section and of less diameter than the interior of the said section, an annular collar engaging the mouth of the sack and projecting in a plane at right angles to the general axis thereof and adapted to close the intervening space 95 between the interior of the receptacle and the exterior of the sack whereby the collar in combination with the sack will form a dividing wall within the receptacle, the lower section of the receptacle being extended downward from the line of separation 100 and forming a chamber below the level of the filter sack, an inlet conduit projecting horizontally within the lower chamber and having its discharge end directed away from the sack, and an outlet orifice in the receptacle in that portion exterior to the sack.

105 2. In a separator tank for vacuum cleaning systems, a receptacle divided into upper and lower portions, an inverted filter sack 110 located in the upper portion, an annular collar engaging the sack and adapted to maintain the sack when inflated with its walls out of contact with the interior of the receptacle, inlet and outlet orifices on opposite sides of the filter sack, the lower portion of 115 the receptacle being extended below the inlet orifice to form a receiving chamber for the material, and a baffle plate interposed between the inlet orifice and the collecting chamber.

120 3. In a device of the character described, a receptacle, an inverted filter sack therein, an outlet orifice above the attachment point of the sack, an inlet conduit extending horizontally into the receptacle below the sack, the said receptacle being extended below the inlet conduit to form a receiving chamber 125 for the material, a deflector interposed between the receiving portion of the receptacle and the inlet conduit and adapted to receive 130

the impact of the incoming current of dust laden air and to protect the contents of the receiving portion of the receptacle from agitation.

- 5 4. In a device of the character described, a receptacle, a baffle located therein dividing the receptacle into a dust receiving chamber below the baffle and a filter chamber above the baffle, a filter sack located in the
 10 filter chamber, an inlet conduit discharging into the receptacle between the baffle and filter sack, and an outlet orifice located above the filter sack.
5. In a device of the character described, 15 a receptacle a baffle therein, a filter sack above said baffle, an inlet conduit discharging intermediate the filter sack and baffle, an outlet conduit leading from the receptacle above the filter sack, the portion of the receptacle below the baffle forming a dirt receiving chamber, and a removable bottom for said chamber.
6. In a device of the character described, 20 a receptacle having an air inlet and an air outlet therein, a filter sack within said re-

ceptacle above the air inlet, the receptacle being extended below the air inlet to form a dirt receiving chamber, a transversely arranged baffle intermediate the dirt receiving portion of the receptacle and the inlet orifice, adapted to receive the impact of the incoming current of air and thereby protect the collection of dirt from agitation. 30

7. In a device of the character described, a receptacle, a baffle therein spaced above 35 the bottom of the receptacle forming intermediate the baffle and the bottom of the receptacle a dirt receiving chamber, an air filter within the receptacle, an air inlet into the receptacle intermediate the baffle and filter, 40 an air outlet from the receptacle, the said filter being located between the air inlet and the air outlet.

In testimony whereof, I have hereunto set my hand this 3rd day of February A. D. 45 1908.

CARL R. GREEN.
